DOOR CONTROL FOR THE REAR LIFTING MECHANISM OF TWO POST LIFTS

Ion V. K. Hott and Kenneth E. Berk, Dayton, Ohio, assignors to The Joyce-Cridland Company, Dayton, Ohio, a corporation of Ohio

Application March 20, 1950, Serial No. 150,696

7 Claims. (Cl. 187—8.62)

1

This invention relates to an automobile lifting mechanism, and more particularly to the lifting mechanisms of the type in which the superstructure is movable into and out of a pit below the level of a floor.

The invention is here shown as embodied in the rear lifting mechanism of a two post lift which is movable into and out of a pit and is of the general type shown in the Webster and Berk application, Serial Number 739,132, filed April 3, 1947, now Patent No. 2,588,597.

One object of the invention is to provide an improved and simplified mechanism for controlling the opening and closing of the doors of the pit.

A specific object of the invention is to provide a door controlling mechanism in which the connection between an actuating device and a door is yieldable to permit the movement of the actuating device with relation to the door when excessive resistance is offered to the opening of the door.

Other objects of the invention may appear as the mechanism is described in detail.

In the accompanying drawings Fig. 1 is a top plan view of a pit enclosing the lifting mechanism, with the doors closed; Fig. 2 is a longitudinal sectional view taken on the line 2—2 of Fig. 1, showing the pit housing partly broken; Fig. 3 is a staggered transverse sectional view taken on the line 3—3 of Fig. 1; and Fig. 4 is a sectional detail taken on the line 4—4 of Fig. 2.

In these drawings we have illustrated one embodiment of the invention and have shown the same as applied to a hydraulic lifting mechanism of a known type, but it is to be understood that the mechanism may take various forms and may be applied to lifting mechanisms of various kinds without departing from the spirit of the invention.

In that embodiment here illustrated the lift is hydraulically operated and comprises a cylinder 5 mounted in the ground below the bottom of a pit 6 with its upper end extending into the pit. A piston 7 mounted in the cylinder has rigidly secured thereto a cross head 8 and parallel rails 9 are secured to the respective ends of the cross head adapted to support the rear axle of an automobile on the lift. The pit may be of any suitable size and shape to receive the superstructure of the lift but preferably it is of an H-shape, having parallel side portions 10 to receive the rails 9 and a transverse portion 11 to receive the cross head 8. The upper ends of these portions of the pit constitute openings in a floor 12

2

through which the cross head and rails may move into and out of the pit. The upper edge of each wall of the pit is protected by an angle bar 13, the upper flange of which is at floor level and which constitutes a door support. Each of the floor openings 10 and 11 is provided with a closure. Preferably each of the side, or parallel, openings 10 is closed by a single door hinged at its outer edge to the adjacent bar 13, as shown at 15. The transverse opening 11 is closed by a pair of doors 16 hinged at their outer edges to the bars 13 at the respective sides of the opening, as shown at 17.

Means are provided for opening the several doors to permit the superstructure to move into and out of the pit and for closing all the doors while the superstructure is in the pit. In the present arrangement the transverse doors 16 are moved to their open positions by contact with the cross head 8 as the lift moves upwardly and are provided with parts 18 to engage and move over the respective edges of the cross head and to then engage the lifting element, or piston 7. The axes about which the doors 16 move are spaced one from the other a distance somewhat greater than the diameter of the lifting element so that when in engagement with the lifting element these doors are supported thereby in inwardly inclined positions and are moved by gravity to their closed positions when the superstructure passes below floor level. The doors 16 are supported in their substantially horizontal closed positions by studs, or rods, 19 mounted on and extending upwardly from the cylinder 5 and each adapted to engage the inner edges of both the doors. These doors, when in their open positions, are so positioned with relation to the transverse opening as to prevent a person working under an automobile on the lift from stepping into the opening.

The opening and closing movements of the side doors 14 are also controlled by the movement of the lifting element and for this purpose there is mounted in the pit an actuating mechanism, the operation of which is controlled by the lifting element and which is so connected with the respective doors 14 that those doors will be opened when the superstructure moves toward the doors from either below or above the same, and will be closed when the superstructure has moved through the floor openings. The connection between the actuating mechanism and the doors includes a yieldable element of sufficient strength to open the doors when the opening movement thereof is unresisted but to

yield and permit the actuating mechanism to move with relation to the doors when the opening movement of the latter is strongly resisted. This actuating mechanism may take various forms. Preferably it comprises a rock shaft 20 extending transversely to the cylinder 5 below the lowermost position of the superstructure and rotatably mounted in bearings 21. Mounted on the shaft 20 adjacent each end thereof is a crank arm 22 the outer end of which is movably connected with the lower portion of a rigid member, or rod, 23, which is pivotally connected at 24 with the corresponding door 14. The crank arm is connected with the rod for movement with relation thereto but is normally held against such movement by spring means. Preferably a bearing member 25 is pivotally connected with the outer end of the crank arm 22 for movement about a horizontal axis and is provided with a vertical opening through which the rod 23 extends, the rod having at its lower end a head, or nut, 26 to retain the bearing member thereon. A compression spring 27 is mounted about the rod between the bearing member 25 and a stop on an intermediate portion of the rod. In the present instance the rod 23 is formed in two parts which are adjustably connected one with the other by a turnbuckle 28 and this turnbuckle constitutes the stop which engages one end of the spring 27. When the crank arm 22 is moved about its axis in a counterclockwise direction, as shown in Fig. 2, and the opening movement of the door 14 connected therewith is resisted, the spring 27 will hold the bearing member 25 against material movement lengthwise of the rod and the door will be opened. Should substantial resistance be offered to the opening movement of the door, as by an automobile so positioned above the lift that one wheel thereof overlaps the door, the spring 27 will be compressed and the crank arm will move with relation to the rod, thus preventing injury to the mechanism and affording sufficient time for the operator to note that the door is not opening and to interrupt the operation of the actuating mechanism.

The means for actuating the rock shaft 20 may be of any suitable character and as here shown it comprises an elongate cam 29 mounted on an elongate member 30 which is rigidly secured to the cross head 8 and extends into the ground below the pit so that it moves with the lifting element. The upper and lower portions of the cam are provided with relatively long inclined cam surfaces, 31 and 32, connected one with the other by a vertical edge portion 33. Rigidly secured to the rock shaft 20 is a second crank arm 34 or cam follower which extends inwardly to a position to be engaged by the cam 29, the crank arm having thereon a roller 35 to provide rolling contact between the same and the cam. The crank arm 34 is so connected with the rock shaft 20 that when the shaft is in its normal lowered position the crank arm will extend at an exact predetermined angle to the upper cam surface 31, such that upon the upward movement of the lifting element and cam the upper cam surface will engage the roller 35 and move the crank arm downwardly about its axis, that is, in a counterclockwise direction as viewed in Fig. 2, thereby moving the crank arm 22 also in a counterclockwise direction to open the doors. Upon the continued movement of the lifting element after the doors have been opened the straight surface 33 of the cam will engage the

roller and hold the crank arm 34 in the position to which it has been moved so as to prevent the doors from closing until the superstructure has passed through the openings in the floor, and the lower cam surface 32 will then engage the roller and permit the crank arm 34 to move in a clockwise direction, thereby permitting the doors to close. As best shown in Fig. 3 the doors when in fully open positions extend inwardly at a slight angle to the vertical so that when the crank arm 34 is released by the cam the doors will move to their closed positions by gravity. As the superstructure moves downwardly from its elevated position the lower inclined surfaces 32 of the cam will engage the roller 35 and move the crank arm 34 again in counterclockwise direction to open the doors 14 and when the superstructure has passed into the pit the upper inclined surface 31 of the cam will engage the roller and permit the doors to close. Preferably a bracket 36 is mounted at one side of the crank arm 34 and provided with a stop, such as a pin 37, to positively limit the upward movement of the crank arm.

Thus it will be apparent that when the superstructure is within the pit all four doors will be closed and will form a smooth and continuous portion of the floor surface. When the lift is in its elevated position the side doors 14 will be closed and the transverse doors 16 will be in inclined positions and in engagement with the lifting element, and when in those positions will prevent the foot of the operator from entering the opening 11.

While we have shown and described one embodiment of our invention, we wish it to be understood that we do not desire to be limited to the details thereof as various modifications may occur to a person skilled in the art.

Having fully shown and described our invention, what we claim as new and desire to secure by Letters Patent, is:

1. In an automobile lifting mechanism, a vertically movable lifting element, a superstructure mounted on said lifting element for movement thereby through an opening in a floor into and out of a pit below the level of said floor, movable closures for said opening, means for moving said closures to open positions including an actuating mechanism below said opening and controlled by said lifting element, and means for operatively connecting said actuating mechanism with one of said closures, said connecting means including a resilient element of sufficient strength to open said closure under normal operating conditions and adapted to yield and permit said actuating mechanism to move with relation to said closure when excessive resistance is offered to the opening movement of said closure.

2. In an automobile lifting mechanism, a vertically movable lifting element, a superstructure mounted on said lifting element for movement thereby through an opening in a floor into and out of a pit below the level of said floor, means for closing said opening including a hinged door, door operating mechanism below said opening controlled by said lifting mechanism and including a crank arm, an actuating member connected with said door, and means for operatively connecting said crank arm with said actuating member, said connecting means including an element which is yieldable under excessive resistance to the opening movement of said door.

3. In an automobile lifting mechanism, a ver-

tically movable lifting element, a superstructure mounted on said lifting element for movement thereby through an opening in a floor into and out of a pit below the level of said floor, means for closing said opening including a hinged door, door operating mechanism below said opening including a crank arm, means including a rock shaft fixedly attached to said crank arm and a cam follower engaging a cam controlled by said lifting mechanism for actuating said crank arm, a door actuating member operatively connected with said door, and means for connecting said crank arm with said actuating member for movement with relation thereto, and spring means to normally prevent the movement of said crank arm with relation to said actuating member and to yield under excessive resistance to the movement of said door.

4. In an automobile lifting mechanism, a vertically movable lifting element, a superstructure mounted on said lifting element for movement thereby through an opening in a floor into and out of a pit below the level of said floor, means for closing said opening including a hinged door, door operating mechanism below said opening and including a rock shaft and a crank arm fixedly mounted on the rock shaft having mounted thereon a cam follower, a cam controlled by said lifting mechanism and engaging said cam follower for actuating said crank arm, a rod pivotally connected with said door, a part connected with said crank arm and slidably mounted on said rod, a stop on said rod between said crank arm and said door, and a compression spring confined between said stop and said part on said crank arm.

5. In an automobile lifting mechanism, a vertically movable lifting element, a superstructure mounted on said lifting element for movement thereby through an opening in a floor into and out of a pit below the level of said floor, means for closing said opening including hinged doors, a door operating mechanism below said opening including a rock shaft having a plurality of crank arms mounted thereon, means controlled by said lifting mechanism for engaging one of said crank arms to rock the other crank arms, rods pivotally connected respectively with a plurality of said doors and to said other crank arms, parts connected with said other crank arms and slidably mounted on the corresponding rods, a stop on each of said rods between its crank arm and its door, and a compression spring confined between the stop on each rod and the part on the corresponding crank arm.

6. In an automobile lifting mechanism, a lifting element, a superstructure comprising a cross member secured to said lifting element and parallel rails secured to the respective ends of said cross member, said superstructure being movable by said lifting element through an opening in a floor including parallel passages for said rails and a transverse passage for said cross member, a pair of hinged doors for closing said transverse passage, said doors being arranged to be engaged and opened by said cross member as the latter moves upwardly, a single hinged door for each of said parallel passages, actuating members connected with the doors for the respective parallel passages, operating mechanism mounted below said opening and controlled by said lifting mechanism, means for connecting said operating mechanism with said actuating members and including resilient elements adapted to yield under excessive resistance to the opening movements of the respective doors.

7. In an automobile lifting mechanism, a lifting element, a superstructure comprising a cross member secured to said lifting element and parallel rails secured to the respective ends of said cross member, said superstructure being movable by said lifting element through an opening in a floor including parallel passages for said rails and a transverse passage for said cross member, a pair of hinged doors for closing said transverse passage and arranged to be engaged and opened by said cross member as the latter moves upwardly, a single hinged door for each of said parallel passages, a rock shaft mounted below said opening, means controlled by said lifting element for rocking said shaft, actuating rods connected with the doors for the respective parallel passages, crank arms secured to said shaft and connected with the respective rods for movement with relation thereto, and springs interposed between the respective crank arms and the corresponding rods to yieldably resist the movements of said crank arms with relation to said rods.

ION V. K. HOTT.
KENNETH E. BERK.
